UNITED STATES PATENT OFFICE.

GEORGE HENRY WHEARY, OF RACINE, WISCONSIN.

TRUNK SHOE-BOX-SECURING MEANS

1,172,230.

Specification of Letters Patent. Patented Feb. 15, 1916.

Application filed October 4, 1913. Serial No. 793,273.

To all whom it may concern:

Be it known that I, GEORGE H. WHEARY, a citizen of the United States, and resident of Racine, in the county of Racine and State of Wisconsin, have invented new and useful Improvements in Trunk Shoe-Box-Securing Means, of which the following is a description, reference being had to the accompanying drawings, which are a part of this specification.

10 This invention relates to improvements in trunk shoe box securing means.

In wardrobe and other like trunks, separate shoe boxes are provided for containing shoes. It is desirable to have these boxes removably secured within the trunk in such a manner as to firmly hold the same against accidental releasing and movement within the trunk during transportation and also to 20 permit the easy removal of the boxes when it is desired to gain access thereto or use the box outside of the trunk.

It is one of the objects of the present invention to provide a trunk shoe box securing means which possesses the features before mentioned and is of simple construction and well adapted for the purpose desired.

25 A further object of the invention is to provide a trunk shoe box securing means which is also adapted to reinforce the portion of the trunk engaged against inward and outward strains.

With the above and other objects in view, 30 the invention consists of the improved trunk shoe box securing means and its parts and combinations as set forth in the claims, and all equivalents thereof.

In the accompanying drawing in which 35 the same reference characters indicate the same parts in all of the views; Figure 1 is a front view of a wardrobe trunk provided with the improved shoe box securing means, one half portion of the trunk being indicated by dotted lines; Fig. 2 is a transverse sectional view thereof taken on line 2-2 of Fig. 1; Fig. 3 is a vertical sectional view of the lower portion of the trunk and box taken on line 3-3 of Fig. 2; and Fig. 4 is a sectional detail view of one of the locking members.

40 Referring to the drawing the numeral 8 indicates a wardrobe trunk, 9 the drawer section and 10 the wardrobe section which is 45 adapted to contain the shoe or other box 11 in the lower portion thereof. The shoe box

is of rectangular form and of a length to easily fit between the side walls 12 of the wardrobe section and in the front portion of the said section to permit garments suspended in the wardrobe section to hang in the rear of the box.

50 In shoe boxes of this type the cover 13 is usually in the rear of the box and is hinged to the bottom portion of the box and extends upwardly in vertical position so that it is necessary to tilt or remove the box from the trunk section in order to gain access to the contents of the box.

55 A snap member 14 holds the cover in closed position and partitions 15 divide the box into a number of compartments for holding shoes.

60 The lower front portion of the box is removably anchored to the front bottom portion 16 of the wardrobe section of the trunk by means of a downwardly extending angular lug 17 which enters a slotted plate 18 mounted on the said bottom portion. The angularity of the lug offsets the lower portion 65 of the lug outwardly from the front portion of the box and permits the tilting of the box outwardly while the lug engages the slotted plate.

65 The upper opposite corner portions of the box are provided with spring actuated bolts 19, the outer beveled ends 20 of which enter bolt openings 21 provided in the loop members 22 which are secured to the inner surfaces of the sides 12 adjacent to the bolts 19. 70 The casings 23 of the bolts are provided with hook extensions 24 which project over the front edges of the loop members and securely lock the trunk sides to the box thus 75 serving to brace and reinforce the trunk 80 sides against inward and outward pressure.

85 The beveled ends of the bolts are inclined in a direction to permit the said ends to snap into the bolt openings of the loop members when the box is swung inwardly into the trunk section, and the inner ends of the bolts project through the bolt casings and are bent upwardly and forwardly to provide 90 releasing handles 25 for withdrawing the bolts from the looped members.

95 In use the box is positioned to insert the depending lug into the slotted plate and the box is then swung inwardly to locked position and in which position it will also serve to reinforce the trunk. If it is desired to gain access to the box it is only necessary to pull inwardly on the bolt handles 100

and tilt the box outwardly or remove it bodily from the trunk section and then open the cover.

While the box has been particularly described as a shoe box it is to be understood that the box may be used for other purposes without departing from the spirit and scope of the invention.

From the foregoing description it will be seen that the trunk shoe box securing means is of very simple construction and is well adapted for the purpose described.

What I claim as my invention is:

1. The combination with a trunk provided with a removable box, of a securing means therefor, comprising a means for removably connecting the bottom portion of the box to the trunk, and locking members removably connecting the upper portion of the box to the opposite sides of the trunk and locking said box portion against inward or outward movement.

2. The combination with a trunk provided with a removable box, of a securing means therefor comprising a means for connecting the bottom portion of the box to the trunk, and locking members connecting the upper portion of the box to the opposite sides of the trunk, said locking members reinforcing the trunk sides against inward and outward strain.

3. The combination with a trunk provided with a removable box, of a securing means therefor, comprising a means for removably connecting the bottom portion of the box to the trunk, loops mounted on the opposite side portions of the trunk, and spring actuated bolts mounted on the box and engaging the loops for removably connecting the upper portion of the box to the trunk and for locking said box portion against inward or outward movement.

4. The combination with a trunk provided

with a removable box, of a securing means therefor, comprising a means for connecting the bottom portion of the box to the trunk, loops mounted on the opposite side portion of the trunk and provided with bolt openings, and bolts mounted on the box and adapted to enter the bolt openings of the loops, the casings of said bolts provided with portions which engage the loops and lock the trunk sides to the box against lateral strains.

5. The combination with a trunk provided with a removable box, of a securing means therefor, comprising a means for connecting the bottom portion of the box to the trunk, loops mounted on the opposite side portions of the trunk and provided with bolt openings, and spring actuated bolts mounted on the box and adapted to enter the bolt openings of the loops, the casings of said bolts provided with projecting hook portions which engage the loops and lock the trunk sides to the box against lateral strains.

6. The combination with a trunk provided with a removable box, of a securing means therefor, comprising an apertured plate mounted on the bottom portion of the trunk, an offset projecting lug carried by the box and entering the plate to form a tiltable connection therewith, loop members mounted on the inner side portions of the trunk and provided with bolt openings, and beveled end spring actuated bolts mounted on the box and entering the bolt openings of the loops, the casings of said bolts provided with projecting hooks which extend around the front edge portions of the loops to lock the trunk sides to the box against lateral strains.

In testimony whereof, I affix my signature, in presence of two witnesses.

GEORGE HENRY WHEARY.
